(57) **CLAIM**

The ornamental design for a process cartridge, as shown and described.

DESCRIPTION

FIG. 1 is a front view of a process cartridge showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a top and right side perspective view thereof;

FIG. 8 is a top and left side perspective view thereof; and,

FIG. 9 is a bottom and left side perspective view thereof.

The broken lines depict environmental subject matter only and form no part of the claimed design.
